US0D1062725S

(12) **United States Design Patent** (10) **Patent No.:** **US D1,062,725 S**
(45) **Date of Patent:** **** Feb. 18, 2025**

(54) **CURVED SCREEN SMART WATCH**

(71) Applicant: **Shenzhen Lancest Technology Co., Ltd.**, Guangdong (CN)

(72) Inventor: **Zhi Li**, Guangdong (CN)

(73) Assignee: **Shenzhen Lancest Technology Co., Ltd.**, Shenzhen (CN)

(**) Term: **15 Years**

(21) Appl. No.: **29/942,415**

(22) Filed: **May 15, 2024**

(51) LOC (15) Cl. **14-02**

(52) U.S. Cl.

USPC **D14/344**; D10/30; D10/70

(57) **CLAIM**

The ornamental design for a curved screen smart watch as shown and described.

DESCRIPTION

FIG. 1 is a perspective view of a curved screen smart watch showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the curved screen smart watch and form no part of the claimed design.

1 Claim, 8 Drawing Sheets
